(57) **CLAIM**

The ornamental design for locking handle for refrigerators, as shown and described.

DESCRIPTION

FIG. 1 is a front, right side and top perspective view of a handle assembly, showing our new design.

FIG. 2 is a right side elevational view thereof.

FIG. 3 is a front elevational view thereof.

FIG. 4 is a bottom plan view thereof, the top plan view being a mirror image thereof.

FIG. 5 is a left side elevational view thereof; and, FIG. 6 is a rear elevational view thereof.

The fastener heads partial door shown in phantom in FIG. 7 is for illustrative purposes only, and forms no part of the claimed design.
